UNITED STATES PATENT OFFICE.

GEORGE H. EDWARDS, VICTOR H. KING, AND HERBERT J. SKIPP, OF PROVIDENCE, RHODE ISLAND, ASSIGNEES TO OSTBY AND BARTON COMPANY, OF PROVIDENCE, RHODE ISLAND, A CORPORATION.

DESIGN FOR A RING, SCARF-PIN, BROOCH, BUTTON, OR SIMILAR ARTICLE OF JEWELRY.

47,485.

Specification for Design.

Patented June 22, 1915.

Application filed November 16, 1914. Serial No. 872,478. Term of patent 3½ years.

To all whom it may concern:

Be it known that we, GEORGE H. EDWARDS, VICTOR H. KING, and HERBERT J. SKIPP, citizens of the United States, residing in Providence, in the county of Providence and State of Rhode Island, have invented a new, original, and ornamental Design for a Ring, Scarf-Pin, Brooch, Button or Similar Article of Jewelry, of which the following is a specification, reference being had to the accompanying drawing, forming part thereof.

The figure is an edge view of a ring, illustrating our new design.

We claim:

The ornamental design for a ring, scarf pin, brooch, button or similar article of jewelry, as shown.

GEORGE H. EDWARDS.
VICTOR H. KING.
HERBERT J. SKIPP.
